(57) **CLAIM**

The ornamental design for a wreath cork cage, as shown and described.

DESCRIPTION

FIG. 1 is a perspective view of a wreath cork cage showing my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top view thereof; and,

FIG. 7 is a bottom view thereof.

The broken line showing of the text on the circular wreath label forms no part of the claimed design.
